UNITED STATES PATENT OFFICE.

THOMAS J. LEVEY, OF BALTIMORE, MARYLAND.

BOTTLE-CAPPING MACHINE.

1,027,262.

Specification of Letters Patent. Patented May 21, 1912.

Application filed May 8, 1911. Serial No. 625,888.

To all whom it may concern:

Be it known that I, THOMAS J. LEVEY, a citizen of the United States, residing at 3903 Eastern avenue, Baltimore, in the State of Maryland, have invented certain new and useful Improvements in Bottle-Capping Machines; and I do hereby declare the following to be a full, clear, and exact description of the invention, such as will enable others skilled in the art to which it appertains to make and use the same.

This invention relates to bottle capping machines, and has for its object to produce a machine of this character which will automatically cap bottles of different lengths without crushing the same, and one which will be more efficient in operation and less expensive to construct than those heretofore proposed.

To these ends the invention consists in the novel details of construction and combinations of parts more fully hereinafter disclosed, and particularly pointed out in the claims.

Referring to the accompanying drawings forming a part of this specification in which like numerals refer to like parts in all the views:—Figure 1 is a view in elevation of a machine built in accordance with my invention; Fig. 2 is a longitudinal sectional view of the power shaft and its clutch connections; Fig. 3 is a cross sectional view of certain of the parts shown in Fig. 2 and illustrating the cam for operating the trip pin; Fig. 4 is a detail sectional view of the parts shown in Fig. 3, but in a different position; Fig. 5 is a cross sectional view on the line 5—5 of Fig. 4; Fig. 6 is a top plan view of the parts shown in Fig. 4; Fig. 7 is a perspective view illustrating the cam action of the clutch operating member; Fig. 8 is a sectional view of the capping head; Figs. 9, 10 and 11 are detail elevational views of certain parts of the capping head; Fig. 12 is a view similar to Fig. 8, but showing the parts in a different position; Figs. 13 and 14 are detail views illustrating the parts shown in Fig. 12 in still other positions; Fig. 15 is a sectional view of the bottle rest or support; Fig. 16 is a view taken on the line 16—16 of Fig. 15; Fig. 17 is a view taken on the line 17—17 of Fig. 15; and, Fig. 18 is an elevational view of the bottle rest detached from its support.

1 indicates any suitable frame-work provided with the power pulley 2 loosely mount-

ed on the shaft 3, provided with the slots 4 around its hub, adapted to receive the clutch member 5, and carried by the member 6 fast on said shaft 3, said members 5 and 6 being provided with the cam 7. The clutch member or sliding dog 5 is normally held in engagement with the slot 4 by means of the spring 8 pressing at one end against the bottom of a slot in said dog, and with its other end against a pin 9 fitted to said slot and carried by the cam 7, as best shown in Fig. 4.

Sliding in a portion of the frame-work 10 under the control of the spring 11, is the clutch operating pin 12 provided with a pivoted dog 13 engaged by the lever 14, controlled by the spring 16 and pivoted as at 15 to the lug 17 attached to the frame-work. The said lever 14 is connected by the link 18 to the foot lever 19, pivoted to the portion 10 of the frame-work as at 20. The said portion 10 carries a trip pin 21 which is in the path of the cam 7, and when the lever 14, under the influence of the foot lever 19, causes the dog 13 to be depressed, the said cam 7 turning in the direction of the arrow shown in Fig. 3, forces said pin 21 downward, causes the same to take against the tail 25 of the said dog 13, to swing the same upon its pivot, and to thereupon disengage the said dog from the extreme end of the lever 14. When the said dog is disengaged as described, the spring 11 forces the pin 12 upwardly and as soon as the operator's foot is removed from the lever 19, the spring 16 returns the lever 14 to its position in engagement with said dog 13, as shown in Fig. 2. The head 27 of the said pin 12, as best shown in Fig. 7, is provided with the cam portion 28 and the straight portion 29, while the sliding dog 5 is provided with a slot 30, the surface 31 of which engages said cam portion 28 as the member 6 revolves, and finally engages the straight portion 29 whereupon the said dog 5 is wholly disengaged from the slot 4 and the shaft 3 ceases to revolve. In other words, so long as the operator does not depress the lever 19, the sliding dog 5 rests against the straight portion 29 of the clutch operating member 27 and the power from the pulley 2 is cut off from the machine. On the other hand, if the operator depresses the foot lever 19, the clutch operating head 27 is also depressed thereupon disengaging the sliding dog 5, and permitting its spring 8 to drive it for-

ward into engagement with a slot 4. This of course, causes the shaft 3 to be rotated from the pulley 2, but since the pivot dog 13 is immediately disengaged from the lever 14,

- 5 the head 27 is immediately returned to the position shown in Fig. 2, and as the sliding member 5 returns to its former position, it becomes through the cam surface 28 automatically again disengaged from the slot 4. 10 In other words, a depression of the foot lever 19 will only cause one revolution of the shaft 3 no matter how long the said lever may be held depressed, and the said lever must be released and again depressed after 15 each rotation of the shaft 3, if additional rotations are desired.

Rigid with the shaft 3 is the crank pin 35 coacting with the connecting rod 36 carrying the cross piece 37 to which is attached the housing 38 having the slide 39 guided by the upper portion 40 of the frame-work. The housing is preferably constructed as shown in Fig. 8 and is provided with the upper portion 41 closed as by the cap 42 25 and carries the spring 43, one end of which fits against said cap and the other end of which fits against the hollow piston like sleeve 44, as best shown in Figs. 8 and 9. The said piston sleeve 44 is provided with 30 the slots 45, and its extreme lower end 46 fits against the upper end 47 of the sleeve 48 having the projecting portion 49 provided with the elongated slot 50, as shown. Passing through the projecting portion 49 is the 35 rod 51 to the upper screw threaded end 52 of which is fitted the cam member 53, having the straight surface 54 and the curved surface 55, as shown. This member 53 is adapted to slide up and down to a limited 40 extent inside the sleeves 44 and 48, as best illustrated in Figs. 12 to 14. Against the straight surface 54 of the member 53 normally rest the toes 56 of the dogs 57 pivoted as at 58, and controlled by the springs 59. 45 Said dogs also have toes 60 which project through the slots 45 and rest against the extreme upper edge 47 of the sleeve 48, as shown. Surrounding the reduced portion 49 of the sleeve 48 is the sleeve 61 provided 50 with the slots 62 to form spring fingers 63. Between the said spring fingers and the rod 51 is the spring 64 for the purpose to be disclosed hereinafter. A pin 65 passes through the elongated slot 66 in the said rod 51 55 through the elongated slot 50 in the reduced portion 49 of the sleeve 48, and through the hole 67 of the sleeve 61 in order to slidingly hold the parts together.

68 represents the usual spring controlled fingers for holding the bottle caps in place preparatory to being crimped upon the bottle head, and the extreme end of the rod 51 is preferably enlarged as at 69 and may be provided with a slight projection 70 for a 65 purpose to be described.

71 represents the usual guiding surface for the bottle head and 72 the cap in position upon the bottle 73.

75 represents a bottle stand or support provided with a stem 76 passing through the projection 77 rigid with the frame-work and having the set or locking screw 78. The said stem 76 is provided with the lugs 79 and the said projection 77 is provided with a bayonet slot 80 through which said lugs 79 are adapted to pass. On each side of the slot 80, the projection 77 has the rests 81 and 82, which are adapted to support the lugs 79 in their adjusted positions, and the enlargement 83 of the stem 76 is adapted to rest also on the upper supports 81, as indicated in dotted lines in Fig. 15. That is to say, the stem 76 may be supported in three positions as follows—with the lugs 79 resting upon the supports 81; with the lugs 79 resting upon the supports 82; and with the enlargement 83 resting upon the supports 81, and each position of the support 75 is therefore adapted to accommodate a bottle of a different length. The set screw 78 serves to lock the support 75 in any position to which it may be adjusted.

The operation of my machine is as follows:—A bottle being placed upon the stand 75, the operator depresses the lever 19, and power being applied to the pulley 2, the said lever 19 through the connection 18 depresses the lever 14; which pulls down the dog 13 and the pin 12, which in turn causes the head 27 to disengage the sliding dog 5, and to thereupon permit the spring 8 to force said dog 5 forward and into engagement with one of the slots 4 in the hub of the pulley 2. The pulley being loose upon the shaft 3 and the member 6 being fast thereon, power is accordingly transmitted to the shaft 3 which turns sufficiently to cause the cam 7 to depress the pin 21 and to thereupon disengage the dog 13 from the lever 14. The spring 11 immediately returns the head 27 to its position shown in Fig. 2, whereupon its cam surface 28 shown in Fig. 7, engages the edge 31 of the dog 5 and causes the latter to be disengaged from the pulley 2, and therefore the power to be cut off. In the meantime, however, the shaft has made one complete revolution and therefore the capping head including the housing 38 has been depressed and returned to its raised position, and this notwithstanding the fact that the operator's foot may have remained upon the lever 19. When it is desired to cause the said capping head to again reciprocate, it is essential that the foot be removed from the lever 19 so that the spring 16 may cause the automatic reengagement of the lever 14 with the dog 13 whereupon a second depression of the lever 19 will cause a second reciprocation of the capping head. A bottle cap 72 having been 130

placed in position on the spring fingers 68 in the manner well known, the housing 38 descends and said cap 72 is slipped over the bottle head in the manner well known. As the capping head continues to descend carrying with it the rod 51, the enlargement 69 and projection 70, if such is employed, presses firmly on the cap 72 against the tension of the spring 64 until the inclined surfaces 90 between the toes 56 and 60 of the dogs 57 strike the inclined cam surface 55 of the member 53. In the meantime, the spring fingers 63 wipe down over the cap and force the same into firm engagement with the rim of the bottle mouth when the parts are in the position best shown in Fig. 12, and the capping operation is complete. This, however, supposes the bottle to be of normal length, and it will be observed that in order for the spring fingers 63 to force the cap 72 into position over the bottle rim, it is necessary that said fingers should be carried by the casing 38 downwardly past the spring-pressed head 69. In order to accomplish this, the said fingers are secured to the sleeve 49 through the pin 65 and elongated slots 50 and 66, and the upper rim 47 of the enlarged sleeve 48 is caught under the hook-like toes 60 of the dogs 57, so that the said fingers 63 move downward with the dogs 57 while the rod 51 and head 69 remain stationary with the bottle head. Should, however, a bottle of abnormal length be placed upon the bottle support 75, then the same would be crushed unless some provision is made to relieve the strain which would be brought upon said head by the continuing downward movement of the housing 38. This strain is relieved in the case of abnormally long bottles by the continued downward movement of the housing 38 and sleeve 61 bringing the pin 65 carried by said sleeve into engagement with the bottom of the slot 66 in the plunger 51. During this movement, the toes 56 of the dogs 57 engage the cam surfaces 55, and swing said dogs outwardly on their pivots 58 sufficiently to shift the toes 60 from engagement with the upper rim 47 of the sleeve 48; thereby releasing said sleeve 48, together with the crimping member 63, and allowing said member to remain stationary during further downward movement of the casing 38. Upon the return stroke of the capping head, all parts of course will be restored to their normal positions shown in Fig. 8. It will thus be seen that the operator may hold the lever 19 depressed so long as he chooses, and the capping head will make only a single reciprocation. And, at the same time, the said capping head will automatically cap a bottle whether it is of an abnormal length or not, during each reciprocation, provided of course a cap 72 is placed in position between the fingers 68

after each reciprocation of the capping head. In other words, the operator may select bottles of a given size at random, place them upon the support 75, and simply depress the lever 19 whenever he wishes the bottles to be capped, and will have the assurance that the bottles will be automatically capped whether they are of uniform size or not. 70

When bottles of radically different sizes are to be capped, the operator merely unscrews the securing means 78, and so adjusts the stem 76 as to accommodate the particular size of bottle to be operated upon. He thereupon secures the stand 75 in place, and may then select the new size of bottles 75 at random, whereupon the capping head will, in the manner above disclosed, cap all 80 of the said new sizes without regard to those of abnormal length.

It is obvious that those skilled in the art 85 may vary the details of construction and the arrangement of parts without departing from the spirit of my invention, and therefore I do not wish to be limited to such features except as may be required by the 90 claims.

What I claim is:—

1. In a bottle capping machine, the combination of a capping housing, means for reciprocating said housing, crimping fingers slidably mounted in said housing, locking means for preventing sliding of said fingers, a capping plunger mounted for limited movement relative to said locked crimping fingers, and means actuated by 95 said plunger for releasing said locking means to permit continued movement of said plunger relative to the housing. 100

2. In a bottle capping machine, the combination of a capping housing, means for reciprocating said housing, a sleeve slidably mounted in said housing, dogs for lockingly engaging said sleeve, a capping plunger slidably mounted in said sleeve, a spring confined between said plunger and sleeve, and a cam actuated by said plunger for releasing said dogs from locking engagement with said slidably-mounted sleeve upon continued movement of said plunger. 105 110

3. In a bottle capping machine, the combination of a capping housing, means for reciprocating said housing, a sleeve slidably mounted in said housing, dogs for lockingly engaging said sleeve, a capping plunger slidably mounted in said sleeve, a spring 115 confined between said plunger and sleeve, a cam actuated by said plunger for releasing said dogs from locking engagement with said slidably-mounted sleeve upon continued movement of said plunger, and a spring for 120 yieldingly resisting sliding of said sleeve upon such release. 125

4. In a bottle capping machine, the combination of a capping housing, means for reciprocating said housing, a sleeve slidably 130

mounted in said housing, dogs for lockingly engaging said sleeve, spring fingers slidably supported on said sleeve, a spring-pressed capping plunger, and a cam actuated by said plunger for releasing said dogs from locking engagement with said sleeve upon continued movement of said plunger.

5. In a bottle capping machine provided with a reciprocating capping housing, the combination of a reciprocating capping plunger; a plurality of spring fingers surrounding said plunger; means for forcing said fingers to descend with said housing while permitting said plunger to remain stationary; and means for releasing said fingers after they have descended a predetermined distance, substantially as described.

6. In a bottle capping machine provided with a reciprocating capping housing, the combination of a reciprocating capping plunger; a plurality of spring fingers surrounding said plunger; means comprising pivoted spring controlled dogs for forcing said fingers to descend with said housing while permitting said plunger to remain stationary; and means comprising a cam surface for moving said dogs after said fingers have descended a predetermined distance, substantially as described.

30 7. In a bottle capping machine, the combination of a capping plunger; means for crimping a cap on a bottle head surrounding said plunger but adapted to move independently thereof; a sleeve provided with a holding rim between said crimping means and plunger adapted to impart said independent movement to said crimping means; a dog adapted to engage said rim to move the same in one direction; and a cam associated 35 with said dog adapted to force said dog out of engagement with said rim, substantially as described.

8. In a bottle capping machine, the combination of a capping plunger having a slot; means for crimping a cap on a bottle head surrounding said plunger; a sleeve between said crimping means and plunger having a slot and provided with a holding rim adapted to engage said crimping means; 45 means passing through said slots for securing said crimping means, sleeve and plunger together and for permitting a slight relative movement between said plunger and sleeve; a dog adapted to engage said rim and to 50 force said crimping means into operative

relation with the bottle cap; and a cam associated with said dog adapted to force said dog out of engagement with said rim when said relative movement has taken place, substantially as described.

60 9. In a bottle capping head, the combination of a capping plunger; a crimping means associated with said plunger; a member having a straight and a cam surface associated with said plunger; a dog having a toe coacting with said straight and cam surfaces; a sleeve surrounding said plunger and provided with a rim over which said dog is adapted to engage; and a connection between said sleeve and plunger for permitting a relative movement between said parts and permitting said cam to force said dog out of engagement with said rim, substantially as described.

70 10. In a bottle capping head, the combination of a capping plunger; a member having a straight and a cam surface associated with said plunger; a dog having a toe coacting with said straight and cam surfaces; a sleeve surrounding said plunger and provided with a rim over which said dog is adapted to engage; spring fingers surrounding said sleeve and plunger adapted to crimp a cap to a bottle head; and a slot and pin connection between said sleeve and plunger for permitting a relative movement between said parts and permitting said cam to force said dog out of engagement with said rim when a bottle of abnormal length is being capped, substantially as described.

75 11. In a bottle capping head, the combination of a capping plunger; a member having a cam surface associated with said plunger; a dog associated with said cam surface; a spring for forcing said plunger in one direction; a sleeve having a member adapted to be engaged by said dog surrounding said plunger; a plurality of spring fingers surrounding said sleeve and plunger and adapted to be moved in one direction by said dog and sleeve; and a second spring between said fingers and plunger, substantially as described.

80 In testimony whereof, I affix my signature, in presence of two witnesses:

THOMAS J. LEVEY.
